FIG. 10

INVENTOR
JOHN E. MALLOY
BY *John E. Malloy*
ATTORNEY

UNITED STATES PATENT OFFICE.

JOHN E. MALLOY, OF PHILADELPHIA, PENNSYLVANIA, ASSIGNOR TO EDWARD G. BUDD MANUFACTURING CO., OF PHILADELPHIA, PENNSYLVANIA, A CORPORATION OF PENNSYLVANIA.

FILE HOLDER.

Application filed December 26, 1925. Serial No. 77,686.

My invention relates to file-holders for supporting files to admit of their convenient manipulation, and particularly to a holder of that type which is adapted to bow or flex a file longitudinally and hold it under tension at a suitable curvature so as to present a curved working face, as required for certain uses, such as for instance, the removal of high spots from a broad and relatively flat surface.

10 The object of the invention is to provide an improved device of this character which embodies simple, efficient and positive means for flexing a file and holding it under tension, and which may be easily and quickly 15 operated for the insertion or removal of the file as occasion requires.

Another object of the invention is to provide a device of this character which may be readily adjusted to accommodate files of 20 different lengths and also to regulate the degree of curvature of a file when the tension is applied thereto, and in which the tensioning means and the adjusting means are separate and independent of each other, so 25 that when the holder is adjusted or set for a given length of file and degree of curvature, the tensioning means may be operated without destroying the adjustment, whereby to permit files of the given length to be quickly 30 inter-changed in the holder and held at the desired curvature therein without a separate resetting of the holder at each change.

A further object of the invention is to provide means for positively locking the tensioning means in operative position, so that the handle of the latter may be used in handling the file without any danger of becoming accidentally displaced and thus relieving the tension and releasing the file.

40 With these and other objects in view, the invention comprises the various novel features of construction and arrangement hereinafter set forth and illustrated in the accompanying drawings, in which—

45 Figure 1 is a side elevation of the preferred form of my improved file-holder, showing the parts in an operative position with the file suitably flexed.

Fig. 2 is a similar view, showing the parts 50 in an inoperative position before the tension is applied.

Fig. 3 is a transverse section on the line 3—3 of Fig. 1.

Fig. 4 is a detailed view of one end of

the holder, showing a modified form of file-gripping device adapted to engage either the shank or butt of a file. 55

Fig. 5 is a side elevation of another embodiment of my invention.

Fig. 6 is a top plan view thereof. 60

Fig. 7 is a fragmentary and horizontal sectional view taken on the line 7—7 of Fig. 5.

Fig. 8 is a fragmentary sectional view through a portion of the toggle, showing the locking device in an operative position. 65

Figs. 9 and 10 are detailed views in transverse section on the lines 9—9 and 10—10 of Fig. 5.

Fig. 11 is a fragmentary view in side elevation of a further form of the invention. 70

Similar numerals refer to similar parts throughout the several views.

Referring to the preferred embodiment of my invention as illustrated in Figs. 1, 2 and 3, my improved file-holder comprises a pair of longitudinally disposed clamping members 1 and 2, provided at their remote ends with gripping devices 3 and 4 for engaging and securely holding the opposite end portions of a file. These gripping devices may be of any suitable form. In the present instance, the gripping device 3 is in the form of a hooked lug which is adapted to embrace the tip end of a file. The other gripping device 4 has a socket 5 for receiving the usual tang or shank at the rear end of a file and is also provided with a hooked lug 6 for receiving and engaging the butt end of a file not having a tang or from which the same has been broken. This gripping device is movably mounted as hereinafter pointed out, so that either the socket 5 or the lug 6 may be brought into operative position, according to the form of the file to be inserted in the holder. 85

The holder is adapted to bear, intermediate of the gripping devices 3 and 4, upon the inner face of the file. To this end the clamping member 2 is preferably formed throughout the greater portion of its length with a flat bearing surface 7, which is adapted to have a continuous abutting contact with the inner face of the file before the latter is flexed. Such an extensive bearing surface is not essential, however, and there may be any suitable bearing upon the intermediate portion of the file. 90

The tensioning means for flexing the file comprises a toggle 8 connecting the adjacent

or inner ends of the clamping members 1 and 2. One link 9 of the toggle is rigid with and projects angularly and rearwardly from the clamping member 2, the link and such clamping member constituting together an elbow lever, which bears on the file by means of the bearing surface 7. The other link of the toggle is constituted by a portion of a hand lever 10, which is connected adjacent its inner end 10 to the link 9 by means of a transverse pivot 11 forming the knuckle of the toggle and which is also connected by a transverse pivot 12 to the inner end of the clamping member 1, the pivot 12 being located between the pivot 11 and the outer or free end of the hand lever. The portion of the hand lever between the pivot 12 and the outer or free end of such lever serves as a handle 13 for operating the toggle and may be provided with a suitable hand-hold or grip 14. The hand lever is preferably in the form of a channel bar, the channel opening toward the link 9 and receiving the pivoted end thereof. The side walls of the channel bear against opposite faces of the link 9 and thus strengthen the knuckle against lateral strain. At its inner end, the hand lever is extended beyond the pivot 11 to form a stop 15, which co-acts with the clamping member 1 to limit the movement 30 of the hand lever.

The clamping member 1 is also preferably of channel bar formation, with its channel opening toward the stop 15 and adapted to receive the same. The sides of the clamping member 1 are extended longitudinally at its inner end to provide transversely spaced ears 16 which embrace the hand lever and are secured to it by the pivot 12. This permits the lever 10 to be moved by its handle 13 to bring 40 the toggle to an operative position with the pivot 12 on or slightly past a dead center with the pivot 11. The stop 15 is then seated in the channel of the clamping member 1 and abuts against such member to prevent the movement of the parts beyond this position.

To hold the parts in operative position against accidental displacement, I provide a suitable locking device which is preferably in the form of a collar 17, slidable longitudinally on the clamping member 1 and adapted to be slipped around the stop 15 to prevent it from being moved away from the clamping member 1 and out of the channel thereof. Within the collar is a spring 18 which bears 55 against the clamping member to hold the collar frictionally thereon against longitudinal movement, while at the same time permitting it to be easily and quickly shifted into and out of engagement with the stop 15, as occasion requires.

The distance between the gripping devices 3 and 4 is varied to enable the holder to accommodate files of different lengths and also to regulate the degree of curvature at which 65 a file is held when the tension is applied.

This is accomplished by a suitable longitudinal adjustment of one of the clamping members. In the present instance, the clamping member 2 is formed in two sections having a screw-thread connection between them by means of a longitudinally disposed threaded pin 19 mounted in a threaded socket 20. The file gripping device 4 is carried by this pin and may be shifted longitudinally by the rotation thereof. 75

It is to be noted that the adjusting means and the tensioning means, above referred to, are separate and independent of each other, so that when the holder is adjusted or set for a given length of file and degree of curvature, 80 the tensioning means may be operated without disturbing the adjustment. This is of particular advantage in that it permits the file to be removed from the holder for sharpening or the like and to be readily replaced 85 therein and held at the desired curvature, and also the interchange of other files of the given length in the holder without the necessity for a separate resetting or adjustment at each change. 90

The socket 5 and the hooked lug 6 are located on opposite sides of the axis of rotation about which the gripping member 4 turns with the threaded pin 19. The rotation of the gripping member thus permits either the socket 5 to be brought into operative position to engage the tang or shank of a file as shown in Fig. 1, or the hooked lug 6 to be brought into operative position to engage the butt end of a file as shown in Fig. 2. 100

In inserting a file in my improved holder, the clamping member 2 is first adjusted by means of the threaded pin 19 and socket 20 to vary the position between the gripping members 3 and 4 to suit the length of the file and to regulate the degree of curvature at which it is to be held. The file is then placed against the bearing surface 7 and introduced between the gripping members and engaged thereby. The parts are then in the position shown in Fig. 2. The clamping of the file within the holder is quickly effected by moving the handle 13 in the direction of the arrow shown in Fig. 2 to operate the toggle, whereby to apply tension to one end of the file 110 through the clamping member 1 and to the opposite end of the file through the elbow lever constituted by the link 9 and the clamping member 2. The file is flexed under this tension, as shown in Fig. 1, and the parts are locked in the operative position there shown by merely shifting the collar 17 around the stop 15. It is to be noted that the handle 13 may then be used for manipulating the file 120 without any danger of becoming accidentally displaced and releasing the tension. 125

In Fig. 4 I have illustrated a modified form of file gripping device 4^a which is mounted intermediate of its ends on a transverse pivot 21 and is provided on opposite sides of the 130

5 pivot with a socket 5^a and a hooked lug 6^a. By rocking the gripping device on the pivot, either the socket or the lug may be brought into operative position to engage a file, and may be effectively held in such position by suitable means, such as a stop 22, carried by the clamping member 2^a, for limiting the rocking movement.

10 In another embodiment of my invention, as shown in Figs. 5 to 10 inclusive, the adjusting means for setting the holder for a particular length of file and degree of curvature, are in the form of a rack 23 and pawl 24 controlling the telescoping of the clamping 15 member 2^b. In this instance, the bearing surface 7^b is relatively small and of convex form and has a relatively narrow contact with the file to facilitate the rocking of the elbow lever.

20 The file-holder also includes a modified form of locking device comprising a transverse pin 25 mounted in corresponding longitudinal slots 26 in the sides of the clamping member 1^b to slide into and out of engagement with a recess 27 in the end of the stop 15^b. A spring 28 is coiled around the pin with its ends in frictional contact with the clamping member to hold the pin against accidental movement. On the ends of the 25 pin are heads 29 which bear against the sides of the clamping member to retain the pin in position and to provide finger-holds for the convenient shifting of the lock.

30 A further embodiment of the invention is shown in Fig. 11, in which the sections of the clamping member 2^c are secured together by a pin and slot connection 30 which permits their relative longitudinal movement. A tooth 31 on one section engages a 35 rack 32 on the other section to hold the sections in any desired adjustment. The pin also permits the sections of the clamping member 2^c to be turned relatively to each other, when the file is disengaged from the 40 holder, to withdraw the tooth from the rack to release the sections and permit them to be 45 shifted to different longitudinally adjusted positions. In this embodiment of the invention, I also show the modified form of 50 file gripping device referred to in connection with Fig. 4.

55 There is also a modified form of spring 18^c for frictionally holding the collar 17^c of the locking device. The spring has its end portions seated in the channel of the clamping member 1^c with one end fastened thereto, as indicated at 33, and the other end free. Intermediate of its ends, the spring is bowed around a transverse pin 34 and projects outwardly beyond the side edges of the channel 60 and is adapted to yieldingly resist the sliding movement of the collar away from its operative or locking position. However, the collar may be shifted to an inoperative posi-

tion by depressing the spring and in that position is frictionally engaged by the spring 65 and held against accidental displacement.

It will be understood that various other changes may be made in the form and arrangement of the parts within the scope of my invention as defined in the appended 70 claims.

Having thus described my invention, I claim and desire to protect by Letters Patent of the United States:

75 1. A file-holder comprising clamping members adapted to engage the opposite ends of a file, and a toggle connecting said members and adapted to apply transverse tension to the file.

80 2. A file-holder comprising clamping members adapted to engage the opposite ends of a file, a toggle connecting said clamping members, and means for operating the toggle to transversely tension the file.

85 3. A file-holder comprising clamping members adapted to engage the opposite ends of a file, tensioning means for operating the clamping members, and means independent of the tensioning means for adjusting the 90 clamping members relatively to each other.

95 4. A file-holder comprising clamping members, file-gripping means carried by the respective clamping members for engaging the opposite ends of a file, means connecting said clamping members for applying tension thereto, and means independent of said last mentioned means for adjusting the file-gripping means of one clamping member 100 relatively to the file-gripping means of the other.

105 5. A file-holder comprising clamping members adapted to engage a file at points spaced apart in the direction of the length of the file, said holder having a bearing against the file intermediate of the points of the engagement of the clamping members therewith, and means including a toggle for applying tension to the clamping members to flex the 110 file.

115 6. A file-holder comprising clamping members adapted to engage the end portions of a file, an elbow lever connected with one clamping member, a toggle connecting said elbow lever and the other clamping member, and a handle to operate the toggle.

120 7. In a file-holder, a file-gripping device having separate means for respectively engaging either the shank of a file or the butt end of a file, and means movably mounting said gripping device to permit either of said gripping means to be brought into operative position.

In testimony whereof I hereunto affix my signature.

JOHN E. MALLOY.
